ADJUSTABLE SILL BLOCK

Theodore L. Smalley, New London, Conn.

Application July 8, 1947, Serial No. 759,491

3 Claims. (Cl. 20—68)

1

The present invention relates in general to window-frame structures and particularly to an improved sill-block for windows having auxiliary sash. More especially, the improved sill-block of this invention is adapted for use with interchangeable storm and screen sash of the type disclosed in my co-pending application Serial No. 741,509, filed April 15, 1947.

An object of the invention is to provide a window sill-block which is of superior construction, which is durable and economical to manufacture and which is adaptable for use with auxiliary storm and screen sash of slightly varying dimensions.

A further object of the invention is to provide a superior sill-block which may be readily attached to or removed from a window sill and which is self-leveling so as to automatically compensate for obliquities of the auxiliary sash, and thereby to automatically form a weather-tight seal therewith.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a front elevation of the outside of a window-frame having auxiliary sash mounted therein and embodying the improved window sill-block of this invention;

Fig. 2 is an enlarged fragmentary view partly in section of the left-hand corner of the window-frame and auxiliary sash shown in Fig. 1, the improved window sill-block being partly broken away to show details thereof;

Fig. 3 is an enlarged fragmentary end elevation in section of the window-frame auxiliary sash and sill-block on line 3—3 of Fig. 2;

Fig. 4 is a perspective view of the upper channel-member of the improved sill-block; and

Fig. 5 is a perspective view of the lower channel-member of the improved sill-block.

Briefly, the present invention relates to an improved sill-block which is adapted to be attached to the sill of a window-frame in which storm and/or screen sash, hereinafter referred to as "auxiliary sash," are mounted, the sill-block being especially designed for and hereinafter described in connection with windows which embody permanent weather-frame and a pair of auxiliary sash mounted in superposed relation-

2

ship in the weather-frame, the auxiliary sash being adapted to be removed therefrom from the inside of the window. The particular weather-frame and auxiliary sash referred to is fully described and illustrated in my above identified co-pending application. It will be understood, however, that the improved sill-block of this invention is not limited to this specific type of window-frame and sash-assembly but has application to window-frames with or without weather-frames and embodying other forms of auxiliary sash.

Referring now to the drawings, Fig. 1 shows a window-frame indicated generally at 10 which comprises spaced-parallel side panels 11, a top panel 12 and a sill 13. The latter is preferably a wooden member although any other material may be used and is provided with the usual outwardly-and-downwardly-sloping top surface 14. Secured to the side panels 11 and to the top panel 12 of the window-frame are weather-frames 15 and 16 respectively which as described in the above identified application are preferably aluminum channels secured by screws either to the inside walls of the sides and top respectively of the window-frame, as is characteristic of the so-called "Boston" type of window, or to the respective blind stops 17 of the window-frame as is characteristic of the so-called "New York" type of window-frame, shown herein. Mounted in the channel-shaped weather-frames 15 and 16 are the upper and lower storm or screen sash 18 and 19 respectively. These auxiliary sash are mounted in the weather-frame in superposed relationship, that is to say, with the upper sash 18 supported on the lower sash 19 and held thereby in the upper part of the window-frame. Moreover, the inside walls of the weather-frame 15, are provided with cutouts so as to permit both the upper and lower sash to be readily mounted in and removed from the weather-frame from the inside of the building, suitable handles 20 being provided on the bottom transverse frame-member 21 of the lower sash 19 as shown in Fig. 3 to lift the latter up over a longitudinal weather-sealing flange adjacent the inner edge of the sill-block. Normally suitable resilient-means such as the leaf-springs 22 (see Fig. 1) mounted in the top weather-frame 16 and engaging on the upper transverse frame-member of the upper sash 18 serve to hold the bottom edge of the lower sash firmly in engagement with the top of the sill-block. As shown especially well in Figs. 2 and 3, the bottom edge 23 of the frame-member 21 of the lower sash 19 is provided with a longitudinal

groove 24 which extends throughout the length thereof and is substantially rectangular in cross section, the depth of the groove 24 being at least equal to and preferably greater than the thickness of the bearing-surfaces of the adjustable sash-supporting means hereinafter described.

Sill-blocks which have been used heretofore with auxiliary sash of this general type have consisted quite generally of solid wooden blocks and while these types of sill-blocks have been satisfactory for specific applications, they have not been readily adapted to general use because of their fixed dimensions.

Referring especially to Figs. 3, 4 and 5, the improved sill-block of this invention is indicated generally at 25 and in general comprises an elongated hollow body substantially rectangular in cross section and consisting of an upper channel-member hereinafter referred to as the "weather-strip means" or "weather-strip channel" 26 and a lower channel-member hereinafter referred to as the "sill-channel" 27, each channel-member being cut preferably to the required length from a continuous length of substantially-channel-shaped stock consisting of an easily-worked sheet-metal material such, for example, as aluminum. The respective channel-members are adapted to be assembled in telescoping relationship, as shown and hereinafter described, by means of vertically-adjustable sash-supporting means 28 which constitute essential elements of the improved sill-block of this invention.

More specifically, the sill-channel 27 of the sill-block comprises spaced-parallel side walls 29 bent up from opposite longitudinal edges respectively of a bottom-plate 30, the width of which is slightly less than the thickness of the frame-member 21 of the lower sash 19. Since the sill-channel 27 is adapted to be mounted on the sloping top surface 14 of the window-sill 13, the bottom-plate 30 of the sill-channel is arranged to make an acute angle with each of its respective upright side walls 29 corresponding to the slope of the window-sill 13 measured from the vertical face thereof so that each side wall of the sill-channel extends upwardly in the vertical plane of the window-sash.

The upper longitudinal edges 31 respectively of each side wall 29 lie in a common horizontal plane, while the mean height of the side walls 29 of the sill-channel is substantially twice the width of its bottom-plate 30. It will be understood, however, that the particular proportions shown and described herein are exemplary only and that variations and modifications thereof are contemplated within the scope of the invention.

As shown especially well in Fig. 5, the bottom-plate 30 of the sill-channel is provided with a pair of vertical apertures 32, each being formed therein adjacent one end of the bottom-plate and on the longitudinal axis thereof for the purpose hereinafter described. Moreover, a pair of transverse cuts or slots 33 are provided in the bottom-plate 30, each slot being located between one end of the plate and the corresponding apertures 32 thereof, and extending upwardly vertically a relatively-short distance into the lower edges of the respective side walls 29. The slots 33 constitute means for permitting drainage from the inside to the outside of the sill-channel and window-frame.

The weather-strip channel 26 of the sill-block comprises a pair of spaced-parallel side walls 34 which in the normal inverted position of the weather-strip channel 26 may be said to be bent

downwardly from the opposite longitudinal edges of the top-plate 35 thereof and at substantially right angles thereto. Each side wall 35 is equal in height and this height is substantially one-half the mean height of the walls 29 of the sill-channel. Further, the over-all width of the weather-strip channel, as measured by the width of its top-plate 35 is greater than the over-all width of the sill-channel by an amount equal substantially to twice the thickness of the sheet-metal channel stock. In accordance with this construction, the inverted-U-shaped weather-strip channel 26 is adapted to be assembled on the U-shaped sill-channel 27 by telescoping the weather-strip channel down over the sill-channel, as clearly shown in Fig. 3, with the inside faces of the side walls 34 of the weather-strip channel fitting closely against the corresponding outer faces of the side walls 29 of the sill-channel.

Formed on the top-plate 35 of the weather-strip channel 26 adjacent its rear or inner edge and substantially perpendicular thereto is a longitudinal weather-flange 36. In the present embodiment, the weather-flange 36 constitutes a flattened longitudinal fold formed in the top-plate 35, but will be understood that the weather-flange may constitute a separate rib-like member welded or otherwise secured to the top-plate. Moreover, the weather-flange is set back from the front edge of the top-plate 35 a distance slightly less than the thickness of the bottom frame-member 21 of the lower sash, so that when the inner face of the latter is seated against the weather-flange 36, which constitutes a stop therefor and is adapted to form a weather-tight seal therewith, the outer face of the bottom frame-member 21 of the lower sash will project slightly beyond the outer side-wall 34 of the weather-strip channel 26. The top-plate 35 is also provided with a pair of vertical apertures 37, each located adjacent opposite ends thereof respectively and arranged to lie in axial alignment with the vertical apertures 32 in the bottom-plate 29 of the sill-channel when the upper and lower channel-members are assembled in telescoped relationship, as indicated in Figs. 2 and 3.

As pointed out above, the weather-strip channel 26 and the sill-channel 27 are adapted to be assembled in telescoped relationship by means of the adjustable sash-supporting means 28. In the present embodiment, two of these sash-supporting means are provided for each sill-block and each comprises a wood-screw having a kerfed head 38, a shank 39, and threads 40 at the lower end of the shank. As employed for assembling the weather-strip channel and sill-channel in telescoped relationship, each screw is adapted to extend down through the respective axially-aligned apertures 37 and 32 thereof with the kerfed heads 38 of each screw extending above the top-plate 35 of the weather-strip channel and the threaded ends 40 of the screws extending through the apertures 32 in the bottom-plate of the sill-channel. By providing a relatively-close fit between the threaded ends 40 of the screws and the edges of the corresponding apertures 32 of the bottom-plate, the threads may be effectively caught on the edges of the apertures to temporarily hold the two channel-members in assembled relationship so as to facilitate transportation and storage thereof. It will be understood, however, that engagement of the threads of the screws with the edges of the corresponding apertures will not interfere with the normal functions of the screws, as hereinafter described.

As assembled thusly on the sill-channel 27, the weather-strip channel 26 is free to telescope up and down vertically thereon, the depending walls 34 of the weather-strip channel engaging the corresponding walls 29 of the sill-channel to prevent lateral displacement of the respective channels. Moreover, the weather-strip channel is adapted to be supported by and guided in its vertical movement by the sash-supporting screws 28 and more especially by the shank-portions 39 thereof which extend through the apertures 37 of the weather-strip channel with a relatively-close fit. However, the fit which each shank makes with the corresponding apertures 37 of the weather-strip channel is not a precision fit, so that there is sufficient freedom of movement between the associated parts as to enable the weather-strip channel 26 to cant or tilt in the vertical plane of the sill-block, for the purpose hereinafter described.

Cooperatively associated with the assembled upper and lower channels 26 and 27 are resilient means indicated at 41 (see Figs. 2 and 3) comprising substantially conical coil-springs, each of which is assembled on one of the screws 28 at opposite ends respectively of the assembled channels. The bottom convolution 42 of each spring is adapted to seat on the bottom-plate of the lower channel 27, while its top convolution 43 is arranged to engage against the underside of the top-plate of the weather-strip channel 26. Moreover, the diameter of the bottom convolution 42 of each spring is substantially equal to the width of the lower channel so that the lower end of the spring is held from transverse movement therein, while the top convolution 43 of each spring closely encircles the adjacent shank-portion 39 of the screw, whereby the latter supports and constitutes guide-means for the upper end of the spring. As mounted in the assembled channels, the conical springs 41 are always partly compressed therebetween and, hence, tend to lift the vertically-movable weather-strip channel 26 upwardly away from the sill-channel 27 into engagement with the underside of the screw heads 38.

The screws 28 have, however, other additional functions over that of temporarily holding the upper and lower channels in assembled relationship. Thus, when the sill-block is mounted on the sill of the window-frame, the screws 28 are adapted to be screwed into the wooden sill 13 to firmly secure the sill-block thereto immediately beneath and in substantially the vertical plane of the superposed auxiliary sash, the sill-block being set back rearwardly from the front face thereof sufficiently, however, to bring the weather-flange 36 of the weather-strip channel in juxtaposition to the rear face of the bottom member 21 of the lower sash and the longitudinal groove 24 in the bottom edge thereof immediately above the kerfed heads 38 of the screws 28. In this connection, it will be noted that the two screws are, in effect, vertically-adjustable posts, the kerfed heads of which constitute bearing-surfaces adapted to enter the longitudinal groove 24 in the bottom sash and to seat against the top wall thereof to positively support the sash a predetermined distance above the window-sill. By inserting a screwdriver or similar instrument in the kerfs of the screw heads and turning the screws, the heads thereof may be raised or lowered vertically and thus compensate for slight variations in the vertical dimensions of the upper and lower auxiliary sash and window-frame.

Thus, weather-tight joints are assured between the top frame-member of the upper sash and horizontal weather-frame and between the mutually-engaging frame-members of the upper and lower storm sash. Moreover, it will be appreciated that since the conical springs 41 are, for all vertical adjustments of the screws 28, under partial compression, the compression forces thereof act both against the weather-strip channel 26 and the sill-channel 27 to hold the plates of these respective members in weather-sealing engagement with the bottom edge 23 of the lower sash and the top surface 14 of the window sill respectively.

As pointed out above, the depth of the groove in the bottom edge 23 of the lower sash is required to be at least equal to and preferably greater than the height of the kerfed screw heads 38 for the successful performance of the sill-block and to insure that this condition will prevail in the commercial production of quantity lots of sash, the grooves 24 are made considerably deeper than the height of the screw heads 38, as illustrated in Fig. 3, so that when the latter are seated against the top wall of the groove 24, the bottom edge of the lower sash will always project downwardly below the plane of the underside of the screw heads. Consequently, the top-plate 35 of the weather-strip channel will engage and be resiliently held by the force of the coil-springs 41 squarely against the bottom edge of the lower sash thereby forming a weather-tight seal therewith, the top-plate 35 being below and clear of the undersides of the screw heads. Moreover, supposing that the bottom edge 23 of the lower sash is not square with the vertical sides thereof, or that the adjusting-screws 28 are improperly adjusted so that the sash is supported in a slightly cocked position in the weather-frame, then the telescoping weather-strip channel 26, being free to tilt in a vertical plane, will automatically adjust its top-plate 35 to conform to the obliquity of the bottom edge of the lower sash and, hence, maintain a weather-tight seal therewith.

Thus, the vertically-adjustable automatically-tilting spring-urged weather-strip channel compensates for irregularities, looseness and other contingencies which so often arise in mounting auxiliary sash in a window-frame, thereby insuring weather-tight seals between all horizontal joints of the auxiliary sash and window-frame.

The assembly of the channel-members of the sill-block and the mounting of the latter on the window sill are believed to be clear from the drawings and the foregoing description and, hence, it will suffice to say that in mounting the storm sash in the weather-frame of the window, the upper sash is inserted up into the upper part thereof from the inside of the window, the lower sash being similarly inserted into the weather-frame with its upper frame-member in engagement with the lower frame-member of the upper sash. Then, by pulling upwardly strongly on the lower sash so as to compress the leaf-springs 22 in the top of the weather-frame, the bottom edge 23 of the lower sash may be lifted up over the weather-flange 36 of the sill-block 25 and swung outwardly to bring its longitudinal groove 24 opposite the heads 38 of the sash-supporting screws, whereupon the lower sash may be allowed to drop down thereon. The removal of the storm sash may be effected in the reverse procedure.

The invention may be carried out in other 75 specific ways than those herein set forth with-

out departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a window-frame having a sill and auxiliary sash provided with a recess in the bottom edge thereof: a sill-block arranged to be mounted on said sill, said sill-block comprising a lower substantially U-shaped channel-member, the bottom of which is adapted to seat on said window sill; an upper substantially U-shaped channel-member slightly larger than said lower channel-member and inverted so as to telescope over said lower channel-member and to move vertically thereon; vertically-adjustable sash-supporting means extending through said telescoped channel-members into said sill to secure said telescoped upper and lower channel-members to said window sill immediately beneath the bottom edge of said auxiliary sash, said sash-supporting means having bearing surfaces projecting above said upper channel-member and arranged to engage in the recess in the bottom edge of said auxiliary sash to positively hold the latter up in said window-frame; and resilient-means mounted within said telescoped channel-members and engageable therewith to urge the upper channel-member thereof upwardly vertically into weather-tight engagement with the bottom edge of said auxiliary sash for all vertical adjustments of said sash-supporting means.

2. In a window-frame having a sill and auxiliary sash provided with a recess in the bottom edge thereof: a sill-block arranged to be mounted on said sill, said sill-block comprising a lower substantially U-shaped channel-member, the bottom of which is adapted to seat on said window sill; an upper substantially U-shaped channel-member slightly larger than said lower channel-member and inverted so as to telescope over said lower channel member and to move vertically thereon; vertically-adjustable sash-supporting means extending through the telescoped upper and lower channel-members of said sill-block into said sill to secure said sill-block to said window sill and immediately beneath the bottom edge of said auxiliary sash, said sash-supporting means having bearing surfaces projecting above the top of said upper channel-member and arranged to engage in the recess in the bottom edge of said auxiliary sash to positively hold the latter up in said window-frame; and resilient-means mounted within said telescoped channel-members and supported on said adjustable sash-supporting means, said resilient-means being engageable with the bottom and top of the lower and upper channel-members respectively to urge

the upper channel-member upwardly vertically into weather-tight engagement with the bottom edge of said auxiliary sash for all vertical adjustments of said sash-supporting means.

3. In a window-frame having a sill and auxiliary sash provided with a recess in the bottom edge thereof: a sill-block arranged to be mounted on said sill, said sill-block comprising a lower substantially U-shaped channel-member, the bottom of which is adapted to seat on said window sill; an upper substantially U-shaped channel member slightly larger than said lower channel-member and inverted so as to telescope over said lower channel and to move vertically thereon, said upper and lower channel-members having axially-aligned apertures in the top and bottom thereof respectively adjacent opposite ends thereof; vertically-adjustable sash-supporting screws long enough to extend through the axially-aligned apertures of said upper and lower channel-members into said sill to guide the vertical movement of said upper channel-member relative to said lower channel-member, and to secure said sill-block to said window sill immediately beneath the bottom edge of said auxiliary sash; heads on said screws constituting bearing surfaces projecting above the top of said upper channel-member and arranged to engage in the recess in the bottom edge of said auxiliary sash to positively hold the latter up in said window-frame; and springs supported on said respective screws between said upper and lower channel-members of said sill-block, said springs being arranged to engage the top and bottom respectively of said upper and lower channel-members to urge the upper channel-member upwardly vertically on said screws into weather-tight engagement with the bottom edge of said auxiliary sash for all vertical adjustments of said screws, said springs being arranged also to yield independently of each other to permit said upper channel to tilt in the plane of its vertical movement so as to automatically conform to an obliquity of the bottom edge of said auxiliary sash.
